(57) **CLAIM**

The ornamental design for a truck rear fender, as shown and described.

DESCRIPTION

FIG. 1 is a perspective view of a truck rear fender showing my new design;

FIG. 2 is another perspective view thereof;

FIG. 3 is a side elevation view thereof;

FIG. 4 is an opposite side elevation view thereof;

FIG. 5 is a top plan view thereof;

FIG. 6 is a bottom plan view thereof;

FIG. 7 is a front elevation view thereof;

FIG. 8 is a rear elevation view thereof; and,

FIG. 9 is an enlarged fragmentary perspective view of the central top and side portion shown in both FIGS. 1 and 2.

The broken lines shown throughout the drawing views are for illustrative purposes only and form no part of the claimed design.
